(57) **CLAIM**

The ornamental design for a flexible elongate member with a portion to receive a bone anchor, as shown and described.

DESCRIPTION

FIG. 1 is a front perspective view of a flexible elongate member with a portion to receive a bone anchor according to an embodiment;

FIG. 2 is a top view of the flexible elongate member with a portion to receive a bone anchor illustrated in FIG. 1;

FIG. 3 is a bottom view of the flexible elongate member with a portion to receive a bone anchor illustrated in FIG. 1;

FIG. 4 is a first side view of the flexible elongate member with a portion to receive a bone anchor illustrated in FIG. 1;

FIG. 5 is a second side view of the flexible elongate member with a portion to receive a bone anchor illustrated in FIG. 1;

FIG. 6 is a rear view of the flexible elongate member with a portion to receive a bone anchor illustrated in FIG. 1;

FIG. 7 is a front view of the flexible elongate member with a portion to receive a bone anchor illustrated in FIG. 1; and,

FIG. 8 is a cross-sectional side view of the flexible elongate member with a portion to receive a bone anchor taken along line 8-8 in FIG. 2.

The broken lines are included for the purpose of illustrating environment and form no part of the claimed design. The dot-dash-dot lines form the bounds of the claimed design and are not part of the claimed design. The diagonal lines in the cross-section do not form part of the claimed design.
